CLAIM

What is claimed is the ornamental design for a combined monkey's fist keychain and zipper assist, as shown and described.

DESCRIPTION

FIG. 1 is a front elevational view of a combined monkey's fist key chain and zipper assist showing my new design;

FIG. 2 is a right side elevational view;

FIG. 3 is a rear elevational view;

FIG. 4 is a left side elevational view;

FIG. 5 is a top plan view;

FIG. 6 is a bottom plan view;

FIG. 7 is a front elevational view of a combined monkey fist key chain and zipper assist showing a second embodiment of my new design;

FIG. 8 is a right side elevational view of FIG. 7;

FIG. 9 is a rear elevational view of FIG. 7;

FIG. 10 is a left side elevational view of FIG. 7;

FIG. 11 is a top plan view of FIG. 7; and,

FIG. 12 is a bottom plan view of FIG. 7.
